UNITED STATES PATENT OFFICE.

REMY DELINIERES, OF LIMOGES, FRANCE.

DESIGN FOR A DISH-HANDLE.

SPECIFICATION forming part of Design No. 15,111, dated July 1, 1884.

Application filed May 2, 1884. Term of patent 7 years.

To all whom it may concern:

Be it known that I, REMY DELINIERES, of the city of Limoges, in the Republic of France, have invented a new and original Design for 5 Dish-Handles, of which the following is a full, clear, and exact description, reference being had to the accompanying drawings, making part of this specification, in which—

Figure 1 represents a side elevation of a 10 tureen with my design, and Fig. 2 an end view of the same.

Similar letters of reference indicate corresponding parts.

The design relates to a handle for dishes of all 15 kinds; and it consists of a handle distinguished by four arms that cross each other in the nature of a crown, said arms having ornamental terminals, and an enlarged knob or button at the point of intersection of the arms.

20 A in the drawings represents the body, and B the cover of a tureen or other dish. Both

the body and cover are provided with handles C, which are distinguished by four inter-crossing arms, b b, that are connected by ornamental terminals d d to the body or cover, and 25 united at their point of intersection by an enlarged portion or button, e, which forms with the arms b b a handle in the shape of a crown.

Having thus described my design, I claim as new and desire to secure by Letters Patent— 30

The design for a dish-handle, consisting of intercrossing arms having ornamental terminals, and an enlarged portion or button at the point of intersection of the arms, substantially as shown and described. 35

In testimony that I claim the foregoing as my invention I have signed it this 9th day of February, 1884.

REMY DELINIERES.
